OPEN BOTTOM, FLOATING TOP SPRING
CUSHION CHAIR OR THE LIKERobert E. Eaton, Burlington, Iowa, assignor to
Chittenden & Eastman Company, Burlington,
Iowa, a corporation

Application April 27, 1935, Serial No. 18,524

7 Claims. (Cl. 155—179)

This invention relates to a spring structure suitable for chairs, davenport, settees, box springs, studio couches, studio davenport, and the like.

5 The chief object of this invention is to provide a spring cushion construction which, in addition to vertically cushioning the load, is of the relatively free top type in that the top of the entire cushion structure may flex as desired or required and which is not rigidly secured to any furniture frame-work except through the cushion coils and which is further characterized by the retention in a centralized position and the prevention of movement of the top to any marked degree in the plane of the top which would normally occur in a free floating top structure.

20 The chief feature of the invention consists in the formation of the spring cushion structure as a unit which may be readily secured at its lower portion, or portions, to the frame-work and its intermediate portions so associated together and retained by the frame-work that the floating top of the cushion unit has the characteristics before set forth.

25 Other features of the invention will be pointed out more fully hereinafter.

The full nature of the invention will be understood from the accompanying drawings and the following description and claims:—

30 In the drawings, Fig. 1 is a top plan view of a portion of the seat arrangement of a chair provided with rearwardly offset arms and a back and adapted to support a T-shaped seat cushion in nested relation, the cushion being removed and the upholstered border and covering fabric being removed from a portion of the figure to illustrate in plan the detailed arrangement of the cushion unit comprising the seat cushion support and the method of anchoring the former to the chair frame.

35 Fig. 2 is a vertical sectional view through the chair structure and particularly the cushion unit, and the covering thereof and is taken approximately in the broken plane 2—2 designated by the arrows in Fig. 1 and in the direction thereof.

40 Fig. 3 is a view similar to Fig. 1 and of a modified form of the invention.

45 Fig. 4 is a view similar to Fig. 2 and of the form of the invention shown in Fig. 3.

50 In the drawings 10 indicates the front rail, 11 the rear or back rail, and 12 the connecting or side rails which are angularly directed and are inclined rearwardly toward each other.

55 At each rear corner is positioned a leg 13 which

extends upwardly and any conventional back structure may be associated therewith. Each front leg 14 is suitably associated with the adjacent front corner. Since the invention is illustrated as applied to a chair, the adjacent ends 5 of the front and side rails are connected by the triangular piece 15, the upper surface of which serves as a support for the lower end of a small double cone type cushion coil 16. The lower turn of this coil thus is suitably anchored as at 100. 10

15 Suitably secured inwardly of each side rail and by triangular brace members 17, is an arm post 18 which extends upwardly from the side rail and at its upper end may be joined to a cross member (not shown) which in turn is suitably supported at the opposite end by the rear leg or an extension thereof. This forms the frame-work for a rearwardly offset and upholstered arm structure and such an arm structure is indicated by the numeral 19 in Fig. 1. 20

25 Reference will now be had to the main connection of the cushion unit to the chair frame. Herein there are illustrated three substantially parallel straps 20 and each has its front end curled as indicated at 21, to form a pivot pin socket. A plate 22 is suitably secured by screws 23, or the like, to the inside of the front rail and includes a pair of spaced sockets 24. A hinge pin 25 may or may not be provided with the angular portion 26 and pivotally connects the plate or 30 bracket 22 to the strap 20. Herein the opposite end of the strap terminates a short distance from the rear rail 11 and each corner is provided with an aperture 27 which seats one end 28 of a small helical 29. 35

40 A bracket 30, herein identical to bracket 22, is similarly secured as at 31 to the inside of the rear rail. Two loops 32 thereon in the present instance, are shown spaced apart axially a distance equal to the width of the strap 20. Each helical 29 has its opposite end 33 engaged in one of the loops of the rear bracket and by reason of this spacing and as shown clearly in Fig. 1, the two helicals connected to each strap are arranged in diverging relation and thus the end of the 45 strap is tensioned against side sway in a direction transverse to the longitudinal axis of the strap. These helicals permit the metal strap 20 to not only move downwardly as a unit but the metal strap is of such character that it also will 50 slightly flex.

55 It will be observed—see Fig. 1—that the spacing of the straps is such that each end strap is considerably remote from the side rail and is not parallel thereto but the straps are parallel 55

to each other. Thus, this type of structure is readily adapted to various upholstered furniture forms.

Suitably secured to each strap, as illustrated in the copending application, Serial No. 755,264, filed November 30, 1934, entitled "Spring cushion construction", of Roy S. Jones, which became Patent No. 2,051,087, issued Aug. 18, 1936 are a plurality of longitudinally aligned cushion coil springs of double conical character. These coil springs in the present disclosure, see Figs. 1 and 2, are indicated by the numeral 35 and if desired, a silencing strip 136 secured by clips 137, to the strap may also be employed.

15 Any other suitable method of mounting the coil springs on the strap, or any means of coil spring support other than a strap may be employed, or any other suitable method of attaching the strap, if utilized, or other means of support to the frame may be employed.

The cushion coils in tandem relation intermediate the top and bottom may be suitably secured together as by a clip 36 which consists of a single length of wire having its free ends turned back upon themselves in embracing relation relative to the adjacent portion of the cushion coil springs as at 37. The upper turn of each coil spring may, if desired, be associated with the next lower turn at the end of the former, as by the knotting 25 38. The cushion coil springs of adjacent rows may be associated together by similar clips 39, the ends 40 of each being turned back as shown in Fig. 1. The upper turns of the cushion coil springs of adjacent pairs in adjacent rows may be united by crossed helicals 41, the ends 42 of which are merely turned back after embracing the upper turn.

A border wire 43 is suitably secured to each of the outermost portions of the border cushion coils and at the top turn of the same and by the clips 44. The border wire is continuous and is relatively free from any other connection thereby forming what may be termed a floating top. There thus results a semi-rigid top structure 40 for the spring unit construction.

In Fig. 1 inasmuch as a T-shaped structure is illustrated, the border wire includes at each forward corner a laterally extending portion 45 clipped as at 46 to the uppermost turn of the corner spring 16. The forwardmost cushion coil 50 35 and the spring 16 at their adjacent tangential upper turns are secured together by the clip 47. The clips 46 and 47 are similar to the clips 44.

To insure considerable additional rigidity in 55 the top of the spring cushion unit, a partition reenforcing border wire element 48 is provided, having U-shaped ends 49 secured by clips 50 to the main border wire at opposite ends of the former. Clips 50 are likewise similar to clips 44. 60 If desired, each of the cushion coil springs 35 adjacent and tangential to the auxiliary partition reenforcing border wire 48 may be similarly clipped together as at 51. It is to be understood the helicals 41 lie slightly below the partition 65 wire 48.

To prevent side to side and/or front to back sway of the floating cushion top structure, each of the appropriate cushion coils adjacent the respective rail may be anchored thereto. The 70 cushion is prevented against side sway by being suitably connected to an intermediate lower turn of a cushion coil at 52 to a chain or similar tying member 53, the other end of which is secured to an anchoring plate 54, suitably secured as at 55 75 to the side rail 12. A similar chain structure,

indicated by the numeral 56, is suitably secured to the anchor 57 secured to the back rail 11 as at 58. Whenever desired or required, additional secondary chains may be connected to these anchorages and connected in turn at the opposite ends to other turns of the same cushion coils and herein numeral 59 indicates said additional chains. Also, the cushion construction may be suitably tied by a forward anchorage or anchorages of similar character 56. It is to be clearly understood that these chains have no function in the sense that they hold the cushion coil or any portion thereof in a relatively compressed relation. They serve primarily as ties to prevent swaying.

It will be noted the chains to the front and rear marginal cushion coils are connected to the latter at a level below the connections between the marginal side cushion coils and the side rails. The auxiliary chain ties, if utilized, are connected 20 to the marginal side cushion coils at approximately the same level as the front and rear chain ties. By reason of the way the views are illustrated in the drawings but one additional chain tie 59 is illustrated clearly and it is intentionally 25 shown slightly offset from the chain tie 53. In plan elevation these chain ties 59 do not appear since they are superimposed by the chain ties 53 in the said figures.

A fabric having the front portion 61 suitably 30 secured to the lower edge of the front rail or to the inside thereof adjacent the lower edge, overlaps the forward face thereof and passes upwardly over the forward border wire as at 62, then extends as at 63 across the top of the semi-rigid 35 floating top and then extends over the rear border wire as at 64 and thence downwardly and rearwardly as at 65 and overlaps the exposed face of the rear rail 11 and is suitably secured to the underface or edge of the rear rail or to the inside 40 face thereof adjacent the lower edge as desired.

Superimposed upon the aforesaid covering and associated therewith may be auxiliary padding or upholstery. Herein 66 indicates a bat which may be of cotton, palm fibre, cocoanut fibre, or 45 other suitable material, that is positioned between the portion 63 or top cover, and an auxiliary top 67, upon which rests an integral seat cushion 68. The latter is diagrammatically illustrated in Fig. 2 and is entirely omitted in Fig. 1. This seat 50 cushion is substantially T-shaped. A suitable amount of padding material 69 is interposed between the front portion 61 of the main cover material and the exposed auxiliary front cover material 70. The latter is looped as at 71 and secured in said loop is a bead forming material 72 55 in the form of a heavy cord, or the like.

The auxiliary front cover material 70 after forming the loop is extended upwardly and outwardly and thence downwardly and rearwardly 60 as at 73, and is secured as at 74 to the top 63 with the auxiliary top 67. Included within this loop 73 is a relatively rigid yet semi-flexible edge construction 75. The latter may be formed of palm fibre, cocoanut fibre, or other suitable material, enclosed within burlap and suitably padded with a sufficient amount of padding. This forms the relatively rigid yet flexible projecting forward edge indicated at 76 in Fig. 1 and the depressed pocket forming portion 77 also indicated therein. The dotted lines in the upper left hand portion of Fig. 2 illustrates how this semi-rigid border structure projects outwardly when the seat cushion 68 is positioned thereon.

From the foregoing it will be noted that there 75

is formed a spring cushion structure which eliminates the use of all spring anchoring, supporting or sustaining webbing except that employed as a silencing strip so that the entire structure 5 is freely exposed from the bottom for cleaning or repair purposes.

Also, there results from the aforesaid construction a mechanical arrangement which has every advantage of a mechanical spring cushion unit 10 in that it does not create lint, or the like, in its use, may be readily cleaned, is readily accessible for repair purposes and is not rigid like the usual mechanical spring structures but it does embody, on the contrary, all the advantages of flexibility 15 inherent in a web type mounted spring cushion arrangement.

As illustrated in Fig. 1, each of the upper turns of the forward cushion coils 35 is not a true circle but is deformed forwardly in an elliptic formation as at 80. This arrangement provides 20 for the overhanging positioning of the forward portion of the border wire relative to the forward cushion coils which of necessity by reason of the mounting at the base thereof, are mounted inwardly of the front rail by reason of the pivotal connection of the strap to the front rail.

This T-shaped form selected for illustration purposes, discloses a construction which inherently is capable of forming arched or double 30 arched front contours along the forward edge indicated by the numeral 76 in Fig. 1, while at the same time utilizing a straight front rail. When such a front curvature is desired, it is to be understood the border wire and the portions 35 indicated at 73, conform to the desired outline and that the top turns of the forwardmost cushion coils are extended beyond that indicated at 80, so as to still maintain contact through the 40 clips with the border wire. In each instance, of course, the seat cushion diagrammatically indicated at 68, would have a correspondingly formed front contour.

It will also be observed that the cushion unit, in each instance where a back is utilized in the 45 chair, or the like, terminates short of the rear rail. The back upholstering terminates as indicated at 85. Similarly, when upholstered arms are provided, as indicated at 19, the cover fabric is inclined downwardly and outwardly toward 50 the side rails to which it is similarly secured and the intervening space nests, as it were, the arm upholstering and this is possible because the side and rear portions of the border wire in a construction of this character, lies within the projected outline of the side and rear rails. It is 55 usually desirable to have the front border wire, or at least certain portions of it, substantially coincide with the projection of the front rail.

It will also be noted that the front border 60 wire is positioned considerably forwardly of the connection 74 indicated in the figures. In certain instances, if and when desired or required by the contour arrangement, additional supplementary springs 16 may be associated with the 65 adjacent forward cushion coils and/or the forward portion of the border wire and suitably supported by bearing on a lower support carried by the front rail. These cushion coils are otherwise relatively free, except for their connection to the spring cushion through the border wire arrangement and by the clips forming said connection, or by connecting said auxiliary spring or springs to the top portion of the adjacent forward cushion coil or coils.

70 In Figs. 3 and 4, there is illustrated a modi-

fied form of the invention and this form of the invention differs in several respects from that illustrated in Figs. 1 and 2, to wit, the overhanging beaded forward edge of the seat structure is omitted. Instead of the seat structure being 5 of T-shaped outline, it is of arcuate or bowed outline. Also, modified forms of tying the several springs of the unit to the frame and remote from the top of the former are different from that illustrated in Figs. 1 and 2, and the latter, 10 if and when desired, includes an adjustable mounting for frame anchoring connection.

Unless otherwise noted, numerals of the 100 series similar to numerals applied to Figs. 1 and 2, are employed to designate similar parts in 15 Figs. 3 and 4. In view thereof, no specific description need be repeated but only the departures from the form of the invention shown in Figs. 1 and 2 will be specified.

In this form of the invention, all the coils 20 135 are illustrated as being of like character. The border wire 143 is suitably secured wherever tangent to one or more of the coils by the clips 144. The forward portion of the border wire is bowed outwardly and the intermediate reenforcing wire 148 is suitably secured to the border 25 wire fore and aft as by clips 150, the ends of said wire being turned back as at 149. In this form an additional auxiliary border wire 202 may be employed, which is suitably associated with the 30 border wire 143 and is connected to the tangential coils 135 by the clips 244.

Resting on the front rail 110 are a plurality, although only one is shown, of auxiliary coils 116 which, if desired, may be and preferably are, 35 anchored by staples, or the like, to the front rail as indicated at 210. It is to be understood that the coil 116 may be similarly secured, if desired. The coil 116 is suitably secured by clips 146 and 246 to the fore portion of the border wire 143 40 and the auxiliary transverse reenforcing wire 202.

The several coils 135 may be arranged in tandem and spaced row relation and suitably connected together as illustrated in Figs. 3 and 4 or 45 as illustrated in Figs. 1 and 2. The coils are suitably secured to the straps 120 and silenced thereon and said straps may be mounted on the front and back rails 110 and 111, respectively, in the same manner as previously set forth 50 for straps 35—see Figs. 1 and 2.

The frame of this chair differs slightly from that shown in Figs. 1 and 2, in that an auxiliary side rail 200 is provided and this is positioned approximately in the plane of the border wire— 55 see Fig. 4. It is so broken away in Fig. 3 to illustrate a modified form of anchorage.

In Figs. 3 and 4, each of the anchorages from the side rail to the immediately adjacent coil 135 consists of the chain portion 153 connected 60 at one end to a spring or small helical 201, in turn connected at 254 to the plate 154 secured to the side rail 112 as at 155. A comparison of the several anchorages in Fig. 3 with those in Fig. 1 will disclose that each plate 154 is provided with 65 a plurality of openings 254, anyone of which may be associated with the end of the small helical 201. The purpose of the provision of these several openings 254 in each plate is that it provides for perfect adjustment, since the chain may be 70 and undoubtedly will be, in each instance, connected to a slightly different portion of a coil 135.

As previously stated, these tying connections from the coils to the side rail are intended as stabilizers and are not employed to normally im- 75.

part any tension or lateral stress upon the coil 135, if it is not laterally displaced. If laterally displaced, then this anchorage or tie becomes operative to oppose undue lateral or side sway. This 5 insures substantially predetermined positioning of the border wire and top of the cushion unit unless displaced by the person sitting thereon and such displacement is thereupon resisted by such tying connections.

10 The right hand portion of Fig. 4 and the lower right hand portion of Fig. 3 illustrates a modified form of anchorage which may, if desired, be employed in the side rail tying connections and/or the front rail tying connections.

15 This type of anchorage includes the plate 157 secured to the back rail 111 as at 158. A small helical 257 has one end connected to said plate in the usual manner and the other end is herein shown connected to two vertically diverging chain constructions. 256 indicates the lower directed chain connected at one end to the coil 135 and at its upper and rearward end to the helical 257. 156 indicates a chain which is connected at its upper end to a superposed turn 25 of the coil 135 to which the lower end of chain 256 is connected, and the lower end of chain 156 is connected to the helical 257. If desired, a single length of chain may constitute the chains 156 and 256 and the adjacent end of the small helical 30 257 may be associated with the appropriate intermediate link in the aforesaid single length of chain.

The remainder of the parts illustrated and indicated by numerals, correspond to similar parts shown in Figs. 1 and 2.

Whenever it is desired to prevent the end rows of springs, when upholstered, from pulling in toward the center, additional and transversely arranged auxiliary border wire means may be 40 provided, see Figs. 3 and 4. In said figures, wires 248 are suitably secured in tangential relation to the coils by clips 251. The U-shaped ends 249 are secured to the adjacent border wire by clips 250.

45 This insures vertical axial compression and expansion of the coils which prevents noise or clicking in the coils in the several springs which occurs when the coils are canted.

While the invention has been described in great 50 detail in the foregoing specification, the same is to be considered illustrative of the invention and not restrictive in character, since it is well recognized that various modifications thereof will readily suggest themselves to persons skilled in 55 this art, and as heretofore pointed out, certain features herein illustrated, may be omitted, for example, the silencing strip or for example, in place of two divergently directed helicals constituting a rear connection for each strap, a 60 single centrally positioned helical may be employed, or two substantially parallel helicals may be employed. Preferably, however, the two diverging helicals are utilized. Also, certain of the 65 clips, such as indicated at 39 and at 36, may be omitted, if and when desired, as well as the auxiliary chains 59.

The invention claimed is:—

1. In a chair or the like structure including a 70 peripheral frame of rails, in combination a spring unit including top border wire means, a plurality of cushion coils arranged in rows and in tandem relation in each row, a resilient bottom support structure for the coils suitably secured at opposite ends to a pair of opposed rails, said coils having 75 their lower portions nested within the frame,

said border wire means and top turns of the coils being operatively interconnected, and means independent of the bottom and connecting certain marginal coils to the frame to prevent undue swaying of the top of the unit, said means including a downwardly and frame directed metallic flexible connection from one turn of a coil toward the adjacent rail, and an upwardly and frame directed metallic flexible connection from a lower turn of the same coil toward the same rail, said 10 metallic connections lying in substantially the same vertical plane, and another metallic flexible connection at one end connecting together the frame directed ends of the other metallic connections and connected at its opposite end to the 15 said rail.

2. In a chair or the like structure including a peripheral frame of rails, in combination a spring unit including top border wire means, a plurality of cushion coils arranged in rows and in tandem 20 relation in each row, a resilient bottom support structure for the coils suitably secured at opposite ends to a pair of opposed rails, said coils having their lower portions nested within the frame, said border wire means and top turns of the coils 25 being operatively interconnected, and means independent of the bottom and connecting certain marginal coils to the frame to prevent undue swaying of the top of the unit, said means being of flexible metallic character and including a plate 30 anchorage for each means and secured to the adjacent rail and provided with a plurality of anchoring portions spaced differently from the rail for selective connection of the flexible metallic means to one of the portions.

3. In a chair or like structure including a peripheral frame of rails, in combination a spring unit including top border wire means, a plurality of cushion coils arranged in rows and in tandem relation in each row, a resilient bottom support 40 structure for the coils suitably secured at opposite ends to a pair of opposed rails, said coils having their lower portions nested within the frame, means independent of the bottom and connecting certain of the coils to the frame to prevent undue 45 swaying of the top of the unit, said border wire means and top turns of the coils being operatively interconnected, a brace member at each forward corner of the frame, an auxiliary coil spring resting thereon, said border wire means having a lateral extension registering therewith, and means connecting at a plurality of locations the outermost portion of the upper turn of the adjacent auxiliary spring to the lateral extension of the border wire means.

4. In a chair or like structure including a peripheral frame of rails, in combination a spring unit including top border wire means, a plurality of cushion coils arranged in rows and in tandem relation in each row, a resilient bottom support 60 structure for the coils suitably secured at opposite ends to a pair of opposed rails, said coils having their lower portions nested within the frame, means independent of the bottom and connecting certain of the coils to the frame to prevent undue 65 swaying of the top of the unit, said border wire means and top turns of the coils being operatively interconnected, said border wire means having portions projecting forwardly at least as far as the front rail, and a plurality of auxiliary springs, 70 each supported at its lower end by the front rail, and having its upper end terminating in the plane of the border wire means and rigidly secured to the latter.

5. In a chair or like structure including a pe- 75

5 peripheral frame of rails, in combination a spring unit including top border wire means, a plurality of cushion coils arranged in rows and in tandem relation in each row, a resilient bottom support structure for the coils suitably secured at opposite ends to a pair of opposed rails, said coils having their lower portions nested within the frame, means independent of the bottom and connecting certain of the coils to the frame to prevent undue 10 swaying of the top of the unit, said border wire means and top turns of the coils being operatively interconnected, said border wire means having portions projecting forwardly at least as far as the front rail, and a plurality of auxiliary springs, 15 each supported at its lower end by the front rail, and having its upper end terminating in the plane of the border wire means and rigidly secured to the latter, said auxiliary springs being positioned between the side portions of the border wire means 20 and the forward portion of the border wire means projecting forwardly beyond the front rail.

6. In a chair or like structure including a peripheral frame of rails, in combination a spring unit including top border wire means, a plurality 25 of cushion coils arranged in rows and in tandem relation in each row, a resilient bottom support structure for the coils suitably secured at opposite ends to a pair of opposed rails, said coils having their lower portions nested within the frame, 30 means independent of the bottom and connecting certain of the coils to the frame to prevent undue swaying of the top of the unit, said border wire means and top turns of the coils being operatively interconnected, said border wire means having portions 35 projecting forwardly at least as far as the front rail, and a plurality of auxiliary springs,

each supported at its lower end by the front rail, and having its upper end terminating in the plane of the border wire means and rigidly secured to the latter, said auxiliary springs being positioned between the side portions of the border wire means, the forward portion of the border wire means projecting forwardly beyond the front rail and being regularly arched from one side portion to the other. 5

7. In a chair or like structure, including, a peripheral frame of rails, in combination a spring unit including top border wire means, a plurality of cushion coils arranged in rows and in tandem relation in each row, a resilient bottom support for the coils and secured at opposite ends to a 15 pair of opposed rails, said coils having their lower portions nested within the frame and their upper portions projecting an appreciable distance above the top plane of the frame, metallic and flexible means independent of the bottom and connecting certain of the turns of the coils, appreciably below the top turns, to the frame to prevent unit 20 swaying of the top of the unit, said border wire means and top turns of the coils being operatively interconnected, the top turns of all coils except 25 the forward marginal coils lying within an area defined by upward projections of the rails, the front of the border wire means substantially overlapping portions of the front rail and the forward marginal coils connected thereto having 30 their top turns extended forwardly substantially as and for the purpose set forth, portions of the top turns and front border means projecting materially beyond the upward projection of the front rail. 35

ROBERT E. EATON.
